DESIGN FOR A MULTIPLE SERVICE HAIR DRIER APPARATUS

Charles W. Beeston, New York, N. Y., assignor to Eastern Laboratories, Incorporated, New York, N. Y., a corporation of New York

Application November 19, 1935, Serial No. 59,653

Term of patent 7 years

To all whom it may concern:

Be it known that I, Charles W. Beeston, a citizen of the United States of America, residing in the city, county, and State of New York, have invented a new, original, and ornamental Design for a Multiple Service Hair Drier Apparatus, of which the following is a specification, reference being had to the accompanying drawing, forming part thereof.

The figure illustrated in the drawing is a front

perspective view of a multiple service hair drier apparatus, showing my new design.

The back of the apparatus has the same appearance as the front, except that the knob and decorations are omitted.

I claim:—

The ornamental design for a multiple service hair drier apparatus, substantially as shown and described.

CHARLES W. BEESTON,
